UNITED STATES PATENT OFFICE.

CHARLES A. STICKNEY, OF ST. PAUL, MINNESOTA.

SPEED-REGULATOR FOR ENGINES.

No. 844,759.

Specification of Letters Patent.

Patented Feb. 19, 1907.

Application filed February 27, 1905. Serial No. 247,567.

To all whom it may concern:

Be it known that I, CHARLES A. STICKNEY, of St. Paul, Ramsey county, Minnesota, have invented certain new and useful Improvements in Speed-Regulators for Engines, of which the following is a specification.

The invention relates to engines, and particularly those of the internal-combustion type.

10 The object of my invention is to provide an improved mechanism for controlling gas-engine valves and the igniter through the speed of the engine.

15 A further object is to provide such a mechanism inclosed within a suitable casing that will effectually exclude dust and dirt and at the same time protect the engine-operator against injury by the moving parts.

20 A further object is to provide a valve and igniter controlling mechanism which will allow the engine to be turned backward, either by design or accident, without injury to the igniter-cam or any of its parts, this result being obtained without any increase in the 25 number of parts employed.

Other objects of the invention will appear from the following detailed description.

The invention consists generally in a valve and igniter regulating mechanism that is 30 simple and compact and capable of being assembled in large numbers and furnished to purchasers or users of the engine as one piece of mechanism, one size being suitable for several sizes of engines.

35 Further, the invention consists in means for locking the exhaust-valve in its open position and at the same time rendering the igniter inoperative should the speed of the engine increase beyond the desired or predetermined limit.

40 Further, the invention consists in a mechanism for applying the power to operate the valves and igniter to the end that a direct-line thrust will be exerted thereon, thus 45 avoiding the use of many connections and indirect transmission of the valve and igniter operating power.

Further, the invention consists in an igniter-controlling mechanism by means of 50 which the production of the spark can be timed with respect to the stroke of the engine.

55 In the accompanying drawings, forming part of this specification, Figure 1 is a vertical longitudinal section of an internal-combustion engine embodying my invention.

Fig. 2 is a vertical section on the line $x-x$ of Fig. 3. Fig. 3 is a vertical section on the line $z-z$ of Fig. 2. Fig. 4 is a vertical section on the line $y-y$ of Fig. 2. Fig. 5 is a detail in 60 section of the governor, taken on the line substantially at right angles to the section-line of Fig. 3. Fig. 6 is a horizontal section on the line $w-w$ of Fig. 1.

In the drawings, 2 represents an internal-combustion-engine cylinder having a base 3, crank-shaft 4, piston 5, and rod 6, fly-wheel 7, and water-tank 8 and carbureter 9, supported above the cylinder.

10 is an inlet-valve having a stem 11, 70 whereon springs 12 and 13 are eccentrically arranged between loosely-mounted buttons 14 and 15, having steps or shoulders 16 against which the outer spring bears and normally holds the buttons against a stem 17 75 and lock-nuts 18 and draws the inlet-valve to its seat. The inner spring bears at one end on the button 15, but is normally out of contact with the other button except when said other button is moved along the stem to lock 80 the valve, at which time the inner spring is placed under compression and unites its force with the outer spring to lock the inlet-valve and hold it closed.

To operate the button 14, an arm 19 is slidably mounted on the stem 17 and connected by a push-rod 20 with a similar arm 21, that is mounted on the stem 22 of the exhaust-valve 23, that is in line with and directly opposite the inlet-valve. A spring 24 on the 90 stem 22 normally holds the exhaust-valve in its closed position. A suitable bearing 25 is provided for the stem 22, and a socket 26 is mounted on the end of said stem wherein one end of the exhaust-valve pusher-rod 27 is 95 loosely carried.

28 represents the igniter, which forms the subject-matter of a companion application for Letters Patent herewith, filed February 27, 1905, Serial No. 247,569, and will not 100 therefore be described in detail herein.

29 is the igniter-rod, that is arranged parallel substantially with the rod 27, both of which exert a direct-line thrust upon the valve and igniter mechanisms operated thereby. It is desirable to control the movement of these pusher-rods and the parts connected therewith through the speed of the engine, and I will now proceed to describe in detail the mechanism which I prefer to employ for this purpose.

30 is a gear secured on the cam-shaft 31

and driven from a pinion 32 on the crank-shaft 4.

42 is a box or casing having bearings for the cam-shaft 31 and provided with a base or flange 42', that is bolted securely to the engine; but is readily removable for substitution or repairs. The valve and igniter operating mechanisms are inclosed in or mounted on this box, and when the parts are assembled each box with the parts carried thereby include a complete mechanism for controlling the valves and igniter, and the boxes and parts being assembled in large numbers can be sold independently of and used upon several sizes of engines. The box incloses the cam-operating mechanism and protects it from dust and dirt and at the same time shields the operator from injury by the moving parts. A removable cover 43 permits convenient access to the box and the operating mechanism therein.

33 is a valve cam-lever pivoted on a shaft 34 and having a socket 35 in one end, wherein the other end of the pusher-rod 27 is loosely carried. On the other side of its pivot from the socket 35 the lever 33 is provided with an antifriction-roller 36 in the path of a cam 37, secured on the shaft 31 and arranged to engage said roller and oscillate 30 said lever once with each revolution of the shaft 31. The oscillation of said lever moves the pusher 27 lengthwise and opens the exhaust-valve, which is immediately closed again by the tension of the spring 24 as soon as the cam 27 passes the roller. It is sometimes desirable to hold the exhaust-valve open, as when the speed of the engine increases beyond the desired limit, and I therefore connect the cam-shaft 31 with a governor 35 mechanism, preferably in the following-described manner:

A beveled gear 38 is secured on the shaft 31 and meshes with a governor-pinion 39, that has a depending hollow stem 40, fitting within 45 a bearing or sleeve 41, that is exteriorly threaded at one end and screwed into the wall of the casing or box 42. Below the stem 40 is a governor-head 44, provided with upwardly-extending webs 45 and a socket 46, 50 wherein the lower end of the stem 40 is inserted and secured by a set-screw 47. A shoulder 48 is provided on the wall of said socket, whereon a governor-head casing 49 is loosely supported and extends down around 55 the head and the governor mechanism carried thereby. Governor-wings 50 are pivoted at their lower ends in the webs 45 and normally stand in a vertical position and are provided with arms 51, that bear upon the 60 lower end of a hollow governor-stem 52, arranged within the stem or governor-shaft 40 and provided at the upper end with a filler-pin 53, that is slidable in a hole 54 (see Fig. 17) through the pinion 39. A pin 55 is provided in the governor-stem and connected by

a spring 56 with an eyebolt 57, provided with a nut 58 in the governor-head. The adjustment of this nut regulates the tension of the spring 56. The governor-stem normally bears upon the arms 51 of the governor-wings, being held thereon by the force of gravity and the tension of the spring 56, and when said wings are thrown outward by the rapid revolution of the governor the stem will be moved vertically to project the pin 53 through the pinion and toward the cam-shaft. A governor-dog 59 is pivoted at 60 within the cam-box and has an arm 61 overhanging the pin 53 to be engaged thereby when it is raised. A second arm 62 is mounted on said dog and provided with a beveled edge 63, adapted to enter a recess 64 in a catch or stop 65, provided on the lower end of the cam-lever 33. A spring 66 normally holds the arm 62 out of the path of the stop 65; but when the governor is driven at a high speed and the pin 53 is raised the arm 62 will be depressed and will engage the catch 65, locking the cam-lever and preventing the exhaust-valve from closing until the speed of 90 the engine has decreased sufficiently to allow the governor to return to its normal position, and during this time the cam 37 will revolve with its shaft without actuating the cam-lever 33.

It is desirable in a mechanism of this kind to provide means for rendering the igniter inoperative and obviating unnecessary drain on the battery during the time the exhaust-valve is held open and the inlet-valve closed, 100 and no fresh charge is allowed to enter the cylinder. For this purpose I provide a lever 67, which I will hereinafter refer to as the "igniter-lever," having a socket at one end to receive the end of the igniter pusher-rod 105 29 and pivoted at a point intermediate to its ends on the shaft 34.

Pivoted at a point intermediate to its ends upon the igniter-lever within the cam-box is a cam-lever 69, having an arm 70, that projects into the path of a second cam 71, which I will designate as the "igniter-cam," secured upon the shaft 31, near the cam 37. A laterally-turned arm 72 is also provided on the lever 69, projecting into the path of the 110 lever 33 to be engaged thereby. A spring 73 connects the lever 69 with the lever 67 and normally holds the arm 70 in engagement with a longitudinally-sliding pin, which I prefer to designate as the "igniter timing pin," slidably supported in a socket 74 in the lever 67. This pin acts as a stop for the arm 70, and when the cam 71 engages the said arm the lever 67 will be oscillated and the igniter-electrode moved lengthwise to close 115 the circuit therethrough. When, however, the lever 33 is rendered inoperative by means of the governor mechanism, as heretofore described, it will engage the arm 72 and move the lever 69 to the position indi- 120 125 130

cated in Fig. 4, where it will be inoperative and out of the path of the cam 71, and consequently the igniter-electrodes will remain separated and the igniter inoperative as long as the exhaust-valve is held open. This construction will also allow the cam-shaft 31 and the crank secured thereon to be revolved backward without affecting the igniter, the arm 70 merely swinging down against the tension of the spring 73 to the position shown in Fig. 4 and allowing the cam 71 to pass without any danger of breaking or disarranging the parts or requiring the use of additional mechanism beside what is employed to produce the successful operation of the igniter. No damage will therefore result to the mechanism should the cam-shaft be revolved backward by accident or design. A compression-spring 75 is preferably provided in the cam-box that normally holds the pin 76 into the path of the lever 67 to act as a yielding buffer therefor.

When the engine is running at normal speed, the igniter is usually adjusted to produce the spark at a time when the piston is about thirty degrees ahead of the center, so that the explosion of the charge will take place at the proper time or just after the engine passes the center. In starting the engine, however, when it is moved slowly, there would obviously be considerable danger, owing to the difference in speed, of the explosion taking place before the engine passed the center and causing it to run backward if the igniter should be operated at the same point in the stroke of the engine, and consequently it is desirable to provide some means for producing what is known as the "late spark," or varying the time of ignition. I therefore provide a recess 77 in the shaft 34, into which the end of the pin 74 is adapted to enter to allow it a greater vertical movement and delay the time of engagement of the cam 71 with the arm 70. This recess is brought into position to receive the pin by rocking the shaft, and to facilitate the operation I provide an arm 78 on said shaft that is capable of making a half-revolution therewith. At the limit of the stroke in one direction the arm and shaft are in "running" position, as shown in Fig. 4. At the end of its stroke in the other direction the arm is in starting position and indicates that the recess 77 will receive the end of the pin and allow a further movement of the arm 70 and a later engagement of the cam 71 therewith. The arm may be suitably marked to indicate to the operator when it is in its starting or running position.

The following is a brief description of the operation of the engine: The arm 78 having been set in the starting position, the operator will set the engine in motion, the formation of the igniter-spark being delayed sufficiently to enable the engine to reach the proper point

in its stroke before the charge in the cylinder is exploded. As soon as the engine is running the operator will throw the arm 78 to the running position, and the stroke of the arm 70 will be limited and the cam 71 will engage it at the proper time to operate the igniter. Should the speed of the engine go beyond the limit desired, the governor-wings will be thrown out by centrifugal force and cause the pin 54 to be lifted and the lever 33 locked and the exhaust-valve held in an open position, as heretofore described. At the same time the secondary spring, mounted on the stem of the inlet-valve, will be placed under tension to aid in holding the inlet-valve closed. At the same time the lever 33 is locked the engagement thereof with the arm 72 will swing the lever 69 to the position shown in Fig. 4, where it will be out of the path of the cam 71 and the igniter will be rendered inoperative, and there will be no waste of the battery energy during the time the exhaust-valve is held open. This operation will be entirely automatic and require no attention on the part of the engine attendant. As soon as the speed of the engine has been reduced sufficiently to allow the governor to return to its normal position the lever 33 will be unlocked and allowed to swing again into the path of the cam 37, and at the same time the arm 70 will return to its normal position in the path of the cam 71, and the operation of the valves and igniter will be resumed and continued as long as the engine maintains its normal speed.

I claim as my invention—

1. The combination, with a gas-engine having inlet and exhaust valves, of an igniter, levers operatively connected respectively with said valves and said igniter, means for operating said valve-lever, means controlled by the speed of the engine for locking said valve-lever in an inoperative position, a secondary lever carried by said igniter-lever and having a limited travel, means for engaging said secondary lever to operate said igniter-lever and igniter, and said secondary lever projecting into the path of said valve-lever and being engaged thereby and held out of the path of said igniter-lever operating means when said valve-lever is locked in its inoperative position, substantially as described.

2. The combination, with a gas-engine, of an igniter, a lever operatively connected with said igniter, a secondary lever pivoted on said igniter-lever, means for engaging said secondary lever to operate said igniter-lever and igniter, and means for regulating the oscillation of said secondary lever and hastening or delaying its engagement by said operating means, whereby the time of the spark formation is varied, substantially as described.

3. The combination, with a gas-engine, of an igniter, a lever operatively connected therewith, a secondary lever carried by said

igniter-lever, means for engaging said secondary lever to operate said igniter-lever and igniter, a sliding pin mounted in said igniter-lever in the path of said secondary lever and 5 a rock-shaft having a recess in one side adapted to receive the end of said pin and whereby the travel of said pin may be increased or decreased according to the position of said rock-shaft and the increase or decrease of the 10 travel of said pin causing a corresponding movement of said secondary lever and a variation in the time of spark formation at the igniter, substantially as described.

4. The combination, with a gas-engine, 15 having an igniter, of a lever operatively connected with said igniter, a secondary lever carried by said igniter-lever, a cam arranged to engage said secondary lever and operate it and said igniter-lever, a sliding pin in the 20 path of said secondary lever and means for regulating the travel of said sliding pin and the stroke of said secondary lever and thereby varying the time of the spark formation for the purpose specified.

25 5. The combination, with a gas-engine having inlet and exhaust valves, of an igniter, levers operatively connected respectively with said valves and said igniter, a shaft geared to the engine-shaft, a cam mounted 30 thereon and arranged to engage said valve-lever, means controlled by the speed of the engine for locking said valve-lever in an inoperative position, a secondary lever carried by said igniter-lever and having a limited 35 travel, a second cam engaging said secondary lever to operate said igniter-lever and igniter and said secondary lever being engaged and held by said valve-lever in an inoperative position out of the path of its cam when said 40 valve-lever is locked by an increase in the speed of the engine.

45 6. The combination, with a gas-engine frame, of a box removably mounted on said frame, a shaft journaled in said box and geared to the engine-shaft, a lever operatively connected with the engine-valves, a cam mounted on said shaft in position to engage said valve-lever, a dog arranged to engage and lock said lever out of the path of the cam, a 50 centrifugal governor geared to said cam-shaft and arranged to operate said dog to lock said lever when the speed of the engine increases beyond a predetermined point, and said cam-shaft, said lever and said governor being 55 carried by said box and removable therewith from said frame.

55 7. The combination, with a gas-engine, of a box having means for securing it to the engine-frame, a cam-shaft journaled in said box and geared to the engine-shaft, levers pivoted on said box and operatively connected with the engine-valves and the igniter, cams mounted on said shaft and arranged to engage and oscillate said levers, a centrifugal 60 governor and geared to said cam-shaft,

means actuated by said governor for locking said valve-lever in an inoperative position out of the path of its cam and means whereby the locking of said valve-lever will render said igniter-lever inoperative also, and said levers, cam-shaft and governor being supported by and removable with said box from said frame, substantially as described.

8. The combination, with a gas-engine having inlet and exhaust valves, and an igniter, of a box secured to the frame of said engine, levers mounted on said box and operatively connected with said valve and igniter, a cam-shaft journaled in said box and geared to the engine-shaft, a centrifugal governor also controlling the movement of said levers and said levers, cam-shaft and governor being removable from said engine upon the detachment of said box therefrom, substantially as described.

9. In a gas-engine, a cam-box having means for attachment to the frame of the engine, a cam-shaft journaled in said box, levers pivoted at a point intermediate to their ends on said box and depending therein in the path of said cam-shaft, said levers at their upper ends having means for attachment to the engine-valves and igniter respectively, and a centrifugal governor mounted on said box and driven from said cam-shaft and having means for locking said levers in an inoperative position, substantially as described.

10. The combination, with a gas-engine frame, of a box having a flanged base for attachment to said frame, and a hand-hole plate through which access may be had to said box, a cam-shaft geared to the engine-shaft and journaled in said box, levers pivoted on said box and depending therein and operatively connected with the engine-valves and igniter, a centrifugal governor mounted on said box and geared to said cam-shaft and means within said box and actuated by said governor for locking said levers out of the path of said cams, substantially as described.

11. In a gas-engine, a cam-box removably mounted on the engine-frame, a cam-shaft journaled in said box and driven from the engine-shaft, valve and igniter levers mounted on said box and operated by said cam-shaft, a governor also mounted on said box and controlling the movement of said levers and said cam-shaft levers and governor having permanent bearings in said box and being attached to the engine or removed therefrom by the attachment or removal of said box, substantially as described.

12. The combination, with a gas-engine having inlet and exhaust valves and an igniter, of a box removably mounted on said engine, a valve-operating shaft geared to the engine-shaft, means actuated by said valve-operating shaft for moving said valves and said igniter, and said valve-operating shaft

and said operating means being mounted on said box and removable therewith from said engine, substantially as described.

13. The combination with a gas-engine having inlet and exhaust valves and an igniter, of a cam-shaft geared to the engine-shaft, means actuated by said cam-shaft for operating said valves and said igniter, a governor controlling the movement of said operating means, and a suitable support removably mounted on the engine-frame and carrying said engine-shaft and said operating means and said governor, whereby all of said parts may be assembled on the engine simultaneously and in a like manner removed, substantially as described.

14. The combination, with a gas-engine

having inlet and exhaust valves and an igniter, of a cam-shaft geared to the engine-shaft, means actuated by said cam-shaft for operating said valves and said igniter, a support removably mounted on the engine-frame and carrying said cam-shaft and said operating means, whereby these parts may be assembled simultaneously on the engine, and in the same manner removed therefrom, substantially as described.

In witness whereof I have hereunto set my hand this 17th day of February, 1905.

CHARLES A. STICKNEY
